(57) **CLAIM**

We claim the ornamental design for an optical end effector, as shown and described.

DESCRIPTION

FIG. 1 is a front top perspective view of an optical end effector;

FIG. 2 is a rear bottom perspective view of an optical end effector;

FIG. 3 is a front elevation view thereof;

FIG. 4 is a rear elevation view thereof;

FIG. 5 is a left-side elevation view thereof;

FIG. 6 is a right-side elevation view thereof;

FIG. 7 is a top plan view thereof; and,

FIG. 8 is a bottom plan view thereof.

The broken lines depict portions of the optical end effector and form no part of the claimed design.
